UNITED STATES PATENT OFFICE.

JOHN ARRAS, JR., OF ST. LOUIS, MISSOURI.

CHAFF-SEPARATOR FOR THRESHING-MACHINES.

SPECIFICATION forming part of Letters Patent No. 629,186, dated July 18, 1899.

Application filed January 30, 1899. Serial No. 703,855. (No model.)

2 all whom it may concern:

Be it known that I, JOHN ARRAS, Jr., a citizen of the United States, residing at St. Louis, the State of Missouri, have invented certain new and useful Improvements in Chaff-Separators for Threshing-Machines, of which the following is a full, clear, and exact description, reference being had to the accompanying drawings, forming part of this specification.

My invention relates to an appliance for threshing-machines whereby the chaff may be separated from the grain and straw and conducted transversely of the machine to separate outlets from those at which the grain and straw are discharged from the machine. My invention consists in features of novelty hereinafter fully described, and pointed out in the claims.

Figure I is a view showing a portion of a threshing-machine in side elevation, with a part of the side wall broken out to illustrate an appliance located therein, portions of the interior apparatus being shown in section. Fig. II is an enlarged detail top view of a part of the deflector screen, plate, and fingers mounted therein. Fig. III is a sectional view taken on line III III, Fig. II. Fig. IV is a side elevation of the chaff-conveyer. Fig. V is a detail view of the chaff-elevator-operating mechanism.

1 designates the body of a threshing-machine, containing the usual fan 2, through means of which the chaff is blown from the grain as it is delivered from the cylinder of the machine.

3 is the usual shaker, located in the rear of the machine-cylinder, from which the grain falls into the endless carrier 4 and is delivered into the shaker-screen 5.

45 My improvement relates solely to an appliance arranged transversely of the machine for removing the chaff from the machine through its own individual outlet, and I will therefore only describe such parts of the mechanism as are shown in detail, as the other parts making up the machine may be of any common construction.

50 6 designates a deflector-plate mounted over the innermost end of the carrier 4. This plate is formed with a downturned end 7 and is

bent to form corrugations 8 on its upper side, the plate 6 containing a transverse bar 9, mounted in which are rearwardly-projecting fingers 10.

55 11 designates a screen provided with a cross-bar 12, that is connected to the plate 6 by hooks 13, the hooks being preferably movably joined to the cross-bar 12 by bolts, so that the parts may be readily disconnected as occasion may demand—such, for instance, as the necessity of replacing any of the parts. The deflector-screen 11 extends downwardly to a point 14, where it is suitably secured.

60 15 designates uprights extending transversely of the threshing-machine, forming a guideway 16 between them. Mounted in these uprights are drums 17 and 17^a, the shafts of which are arranged in approximately the same horizontal plane. The drums 17 and 17^a receive an endless carrier 18, that travels on them and is capable of being impelled in obverse or reverse directions.

65 19 designates a drive-shaft provided with a pulley 20, located exterior of the threshing-machine and adapted to receive a drive-belt, through means of which the shaft 19 may be propelled. On the shaft 19 is a bevel-pinion 21, that meshes with a bevel-pinion 22 on a shaft 23. The opposite end of the shaft 23 is provided with a pulley 24, that receives a belt 25.

70 The belt 25 extends from the pulley 24 to a pulley 26, mounted on the shaft of the drum 17^a. By this described mechanism the conveyer 18 is driven when power is applied to the drive-pulley 20 to impel the shaft 23 and impart motion to the belt 25. When the belt 25 is arranged on the pulleys 24 and 26, as shown in Fig. IV, the conveyer 18 is caused to travel in one direction, and the chaff in

75 passing to said conveyer is blown against the deflector-plate 6 and deflector-screen 11 and is carried to one side of the threshing-machine, while if the belt 25 be crossed the conveyer 18 will be caused to travel in the opposite direction and deliver the chaff at the opposite side of the machine. The fingers 10, located between the deflector-plate 6 and the deflector-screen 11, are designed to permit the

80 85 90 95 100 descent of any grain that may be thrown beyond the end of the shaker 3, so that the said grain may fall into the shaker-screen 5, while

at the same time these fingers prevent the descent of the straw through the chaff-separator.

I claim as my invention—

1. A threshing-machine comprising a deflector-plate, a deflector-screen against which the chaff from the grain is directed, and a conveyer arranged transversely of the machine onto which the chaff is deposited from said deflector plate and screen, and whereby it is discharged from the side of the machine; substantially as described.
2. A threshing-machine comprising a deflector-plate, and a deflector-screen against

which the chaff from the threshed grain is directed, fingers arranged intermediate of said deflector plate and screen, a conveyer arranged transversely of the threshing-machine onto which the chaff is deposited from said plate and screen, and whereby it is discharged from the machine, and means for driving said conveyer; substantially as described.

JOHN ARRAS, JR.

In presence of—

E. S. KNIGHT,

N. V. ALEXANDER.

Correction in Letters Patent No. 629,186.

Affidavit having been filed by the patentee in the matter of Letters Patent No. 629,186, issued to John Arras, Jr., July 18, 1899, for an improvement in "Chaff Separators for Threshing Machines," in words and figures, as follows, to-wit:

STATE OF MISSOURI, } ss.:
CITY OF ST. LOUIS. }

John Arras, Jr., being duly sworn, deposes and says that he is the applicant whose deposition forms a part of application for Letters Patent No. 629,186, issued on the 18th day of July, 1899, to himself for Improvement in Chaff Separators for Threshing Machines; that the statement contained in his deposition that he is "a resident of the City of St. Louis, in the State of Missouri," is erroneous, and should be (that he is a resident of Columbia, in the County of Monroe, and State of Illinois); that this error arose from inadvertence, or mistake, and with no intention to deceive; that this affidavit is made for the purpose of rectifying said error in giving his residence as that of the City of St. Louis, in the State of Missouri, instead of Columbia, in the County of Monroe, and State of Illinois; and that he desires this affidavit to be a part of the record.

JOHN ARRAS, JR.

Sworn to and subscribed before me this 9th day of October, 1899. My term expires on February 1, 1902.

[SEAL.]

JOSEPH H. ZUMBALEN,
Notary Public.

The same has been placed on file with the papers in the case and a copy attached to said Letters Patent and the printed copies thereof in compliance with the request of the patentee.

Signed, countersigned, and sealed this 28th day of November, A. D., 1899.

[SEAL.]

WEBSTER DAVIS,
Assistant Secretary of the Interior.

Countersigned:

C. H. DUELL,
Commissioner of Patents.
